COMBINED SOAP BAR CONTAINER AND COVER THEREFOR

Tedd Theodore Thomas, New Canaan, Conn., assignor to Colgate-Palmolive Company, New York, N.Y.

Filed May 16, 1974, Ser. No. 470,454

Term of patent 14 years

Int. Cl. D9—03; D23—02
U.S. Cl. D6—89

FIG. 1

FIG. 2

FIG. 3

FIG. 4

FIG. 5

FIG. 7

FIG. 6

FIG. 8

FIG. 9

FIG. 1 is a front, left side perspective view of a combined soap bar container and cover therefor embodying my new design;

FIG. 2 is a front, left side perspective view thereof with the cover in a raised position;

FIG. 3 is a top plan view thereof;

FIG. 4 is a bottom plan view of the cover shown separately for clarity;

FIG. 5 is a top plan view thereof with the cover removed for clarity;

FIG. 6 is a front elevational view thereof, the rear being identical;

FIG. 7 is a left side elevational view thereof;

FIG. 8 is a right side elevational view thereof; and

FIG. 9 is a bottom plan view thereof.

I claim:

The ornamental design for a combined soap bar container and cover therefor, as shown and described.
